UNITED STATES PATENT OFFICE.

LEVI M. BOWMAN, OF TULSA, OKLAHOMA, ASSIGNEE OF ONE-HALF TO GEORGE T. MARTIN, OF TULSA, OKLAHOMA.

NOVELTY ADVERTISING DEVICE.

1,126,373.

Specification of Letters Patent. Patented Jan. 26, 1915.

Application filed June 13, 1914. Serial No. 844,915.

To all whom it may concern:

Be it known that I, LEVI M. BOWMAN, a citizen of the United States, residing at Tulsa, in the county of Tulsa and State of Oklahoma, have invented certain new and useful Improvements in Novelty Advertising Devices, of which the following is a specification.

This invention relates to new and useful improvements in novelty advertising devices, and has for its principal object to provide an advertising device on which light figures are caused to travel over the smooth surface of glass or similar material by means of a motive power which is not apparent.

Another object of this invention is to provide a device in which the figures are made to apparently walk.

A further object of the invention is to provide a novel means for actuating the mechanism controlling the operation of the figures. With these and other objects in view, the invention consists in the novel combination and arrangement of parts which will be fully set forth in the following specification and accompanying drawings, in which,

Figure 1 is a transverse sectional view of an advertising device constructed in accordance with this invention, Fig. 2 is a view similar to Fig. 1, of a modified form of advertiser, Fig. 3 is a top plan view of the modified form of the device, Fig. 4 is an enlarged detail sectional view of the arm of the modified form, Fig. 5 is an enlarged detail view of the contact, Fig. 6 is a transverse sectional view taken on line 6—6 of Fig. 5, and Fig. 7 is an enlarged detail view of the end of the arm illustrating the method of securing the magnet thereto.

Referring now to the drawings by characters of reference, the numeral 1 designates as an entirety the main casing of the device, which comprises the tapered body portion 2, having the bottom 3 secured thereto. This tapered body portion is provided at its upper terminals with the lateral flange 4, the free edge of which terminates in the inturned portion 5, having its free edge rabbeted as at 6. This rabbeted edge is arranged to form a support for the glass cover 7 as clearly illustrated in Figs. 1 and 2.

Secured centrally of the casing 1, is the 55 casing 8, which forms the cover in which the driving mechanism of the device is held.

Rotatably mounted centrally with relation to the casing 1 is the shaft 9 having the angular extension 10 formed at the 60 upper terminal thereof. The lower end of the shaft 9 is journaled in a suitable bearing and is arranged to be driven by the mechanism carried in the casing 8, hereinbefore referred to.

65

A suitable bracket 11 is secured to the casing 1 and is prevented from accidental movement by means of the brace 12. This bracket 11 is arranged to form a support for the upper terminal of the shaft, and the 70 free terminal of the bracket is provided with the enlargement 13 having the internal bore 14 through which the shaft 9 extends.

Suitable magnets are supported at the 75 free end of the arm 10 and are arranged to attract articles which are placed on the cover 7.

Secured to the bracket 11 is a suitable insulated block 15 carrying the contact plate 80 16 which is formed of a strip of spring brass and connects to the binding post 17 in any suitable manner. This contact plate is arranged to engage the copper, or other suitable metal, ring 18 which is carried by 85 the fiber sleeve 19. This ring 18 is formed with an opening which is arranged to break an electrical circuit when the device is in use. The fiber sleeve 19 is mounted on the shaft 9 and is arranged to rotate therewith 90 so that the ring 18 will make and break the circuit intermittently. This ring 18 is arranged to contact with the binding post 20, and thus it will be seen that the wires 21 and 22, which lead from the batteries 23 95 to the magnet, may be connected to the respective contact plates as clearly illustrated in Fig. 5.

The electromagnet 38 is used in conjunction with a suitable permanent magnet designated by the numeral 33, and this magnet 38 is intermittently energized and deenergized through the action of the contact ring 100 18 and plate 16. It will thus be seen that when the device is in operation the permanent magnet will carry an article completely around while the electromagnet is designed 105 to carry the article a portion of the revolu-

tion, at which time the circuit is broken and the article left until the next complete revolution of the arm 10, at which time the magnet is again energized and attracts the article. In this form of device the same is used preferably in conjunction with two articles which are controlled by the electromagnet so that when the magnet is deenergized the object which is left is pushed forward by the object which is being moved such a distance as to overcome the space of deenergization, thereby placing the object which has been left in such a position that upon the energization of the magnet the same will be attracted and carried around to repeat the operation. This electromagnet 38 is connected by the wire 39 to the wire 22 which in turn is connected to the binding post 20, and thus through the contact plate 15 and wire 21 to the batteries or other suitable source of power supply. The opposite pole of the battery is then connected through the medium of the wire 40 to the casing 8 and thereby a ground circuit is formed which completes the circuit through the magnet when the plate 16 and ring 18 are contacting.

In the modified form of the invention the shaft 9 is provided with a longitudinal bore 24 through which the shaft 25, carrying the crank arm 26 at its upper terminal, extends. This shaft 25 is driven by means of the gear 27 which in turn is driven by the gear 28 carried by the shaft 29. The opposite terminal of the shaft 29 carries the gear 30 which meshes with the gear 31 and the gear 31 is carried by the shaft 9. Thus it will be seen that when motion is imparted to the shaft 29 from the mechanism carried within the casing 8, the gears 27 and 31 will be driven by means of the gears 28 and 30, and owing to the fact that the gear 27 of less diameter than the gear 31, it will be apparent that the shaft 25 will be driven at a greater rate of speed than the shaft 9.

Rotatably mounted at the free end of the extension 10 is a magnetary element 32 to which are secured the permanent magnets 33 as clearly illustrated in Figs. 4 and 7. A suitable lateral extension 34 is formed on the member 32 and carries the stud 35 to which the link 36 is connected. The opposite terminal of the link 36 is connected to the stud 37 carried by the crank arm 60 and it will thus be apparent that when the shaft 25 is rotated motion will be imparted to the member 32, thus causing the magnet to move with relation to the arm 10. It will be apparent from the foregoing that in use, the mechanism carried within the casing 8 will set the shaft 9 in operation, which will cause the arm 10 to swing around in the space formed between the flange 4 and the glass 7, thereby carrying

the magnet in a circular track and causing light objects, which may be easily attracted by magnetism and which are stood on the surface of the glass, to be carried around. In the use of the modified form of the invention the object which is carried on the surface of the glass is provided with feet having a material which is easily attracted by magnetism therein.

It will thus be evident that the motion imparted to the magnet carrying element 32 through the crank 37 and link 36 will cause said member to oscillate thereby intermittently swinging the magnets forward and thus the feet of the objects which are attracted by the magnets to move forward intermittently thereby giving the objects the appearance of walking.

While in the foregoing there has been shown and described the preferred embodiment of this invention, it is to be understood that such changes may be made in the combination and arrangement of parts as will fall within the spirit and scope of the invention as defined in the appended claims.

Having thus described my invention, I claim:

1. An advertising device including a casing, a flange formed at the upper edge of the casing, the free edge of the flange being upturned, an insulating plate carried by the upturned edge of the flange, a shaft rotatably mounted centrally of the casing, an arm carried by the shaft, a magnetary member pivotally mounted on the free end of the arm, magnets carried by the magnetary member, means within the casing to cause the shaft to rotate, a second shaft journaled in the first mentioned shaft, a lateral extension on the magnet carrying member, a crank arm carried by the second mentioned shaft, a link connecting the crank arm with the lateral extension on the magnet carrying member, and means to cause the second shaft to rotate at a greater rate of speed than the first mentioned shaft, thereby imparting motion to the magnet carrying member.

2. An advertising device including a casing, a flange at the upper edge of the casing, an insulating plate carried by the casing and spaced from the flange, a shaft rotatably mounted centrally of the casing, an arm carried by the shaft, a magnet carrying member carried by the free end of the arm, said magnet carrying member being pivotally mounted thereon, a lateral extension on the magnet carrying member, magnets carried by the magnet carrying member, a shaft extending centrally through the first mentioned shaft, a crank arm at the upper end of the second mentioned shaft, a link connecting the second mentioned crank arm with the extension on the magnet carrying member, and means to impart motion to both of the shafts and drive the second men-

tioned shaft at a greater rate of speed than the first mentioned shaft, thereby causing the magnet carrying member to oscillate.

3. An advertising device including a casing, a shaft journaled in the casing and centrally thereof, a flange at the upper edge of the casing, an insulating plate carried by the flange in spaced relation thereto, an arm carried by the upper terminal of the shaft, 5 a permanent magnet secured to the arm, and an electro-magnet secured to the arm, 10 means to furnish electric power to the elec-

tro-magnet, means to cause the shaft to rotate and thereby swing the arm in a horizontal plane, and a contact carried by the 15 shaft and by the casing to complete the circuit through the electro-magnet.

In testimony whereof I affix my signature in presence of two witnesses.

LEVI M. BOWMAN.
